RECEPTACLE FOR DAMP CLOTHS

Steven B. Schuler, Mukwonago, and Archie W. Leighton, Waterford, Wis.

Application March 30, 1948, Serial No. 18,016

6 Claims. (Cl. 312—140.4)

1

This invention relates to improvements in receptacles for damp cloths.

In taverns, lunch counters, kitchens and the like, it is common practice to use a cloth for wiping off wet surfaces. Due to the absorbing qualities of the cloth, it soon becomes saturated, and though it may be frequently wrung out, it nevertheless remains damp.

Tavern operators are faced with a particular problem with regard to the cloth they use to wipe off the tops of bar fixtures. This cloth comes in contact with a variety of substances such as cigarette ashes and the like, and with liquids such as beverages which have been spilled on the bar. Thus, bar cloths soon become malodorous as well as unsanitary. For lack of a better place in which to keep the bar cloth, it is often left in the trough which conventionally extends along the inner margin of the top of the bar, and this is obviously objectionable. When the bar cloth is not placed in the abovementioned trough, it is often thrown into the under part of the bar out of view of the patrons. While this last mentioned expedient serves to hide the cloth from view, it is still subject to the objection that washed glassware is usually stored under the bar and contact of clean glassware with a contaminated bar cloth may result in contamination of the glassware and danger to the health of the ultimate user thereof.

With the above in mind, it is a general object of the invention to provide a readily accessible, sanitary receptacle for damp cloths, which receptacle may be mounted in any place convenient to the user.

A further object of the invention is to provide a receptacle of the class described which is adjustable to conform to the contour of a variety of surfaces to which it may be attached.

A further object of the invention is to provide a receptacle of the class described which is provided with means for mounting the same inconspicuously on the under side of a bar fixture.

A further object of the invention is to provide a receptacle of the class described, which is formed with means in all of the wall portions thereof to provide for ventilation of a cloth stored therein.

A further object of the invention is to provide a receptacle of the class described which is simple and easy to manufacture, which is neat in appearance, and which is otherwise well adapted for the purposes described.

With the above and other objects in view, the invention consists of the improved ventilated receptacle for damp cloths, and all of its parts and

2

combinations, as set forth in the claims, and all equivalents thereof.

A clear conception of the construction of the improved receptacle may be had by referring to the drawing accompanying and forming a part of this specification wherein like reference characters designate the same parts in all of the views:

Fig. 1 is a side view of the improved receptacle attached to the underside of that portion of a bar fixture adjacent the trough thereof, portions of the bar and of the receptacle being broken away and shown in section;

Fig. 2 is a top view of the improved receptacle; and

Fig. 3 is a view looking into the open end of the receptacle, taken along the line 3—3 of Fig. 1.

Referring to the drawing, the numeral 5 indicates the main body portion of the improved receptacle. The body portion 5 preferably consists of a pair of substantially parallel perforated side walls 6 (each side wall 6 being formed along a portion of its upper edge with an outwardly extending flange 7), a perforated end wall 8, and a perforated bottom 9. There is also an open end 23 opposite the end wall 8. The flanges 7 are provided with apertures 10 to facilitate mounting of the receptacle by any suitable means such as by screws 11, in any convenient place.

It frequently happens that it is desired to attach the improved receptacle to a surface having an irregular contour. Such an instance occurs in taverns when it is desired to attach the receptacle to the under side of the inner margin of a bar fixture. Most bar fixtures are formed

with a trough, such as is shown at 12 in Fig. 1, along their inner margins. The depth of the trough 12 may vary, however, on different bar fixtures. In order to provide a neat appearing closure for the portion of the main body 5 of

the receptacle which extends inwardly of the trough 12, and to provide a closure which is adjustable to conform to any trough depth, a substantially U-shaped collar or extension member 13 is provided. The collar or extension member 13 comprises a pair of side walls 14 of suitable length, and an end wall 15. The side walls 14 are formed along their upper edges with outwardly extending flanges 16, and the end wall 15 is formed along its upper edge with an outwardly extending flange 17. The flanges 16 are provided with apertures as at 18 to provide for attachment to the underside of a bar fixture, by means such as the screws 19, as shown in Figs.

1 and 3.

Extending vertically on a central portion of

each side wall 14 and on the end wall 15 of the collar 13 are elongated slots 20. Fixedly connected to and projecting outwardly from the side walls 6 and from the end wall 8 of the main body portion 5 adjacent the upper margin thereof, are screws 21, which extend through the slots 20. The collar 13, before attachment thereof to the bar fixture, is vertically slideable on the end of the main body portion 5 and is guided in said sliding movement by the relationship of the screws 21 with the slots 20. The screws 21 are provided with wingnuts 22 for locking the collar 13 in any selected position of vertical adjustment.

In use, the improved receptacle may, if desired, be attached by means of the screws 11 which support the main body portion 5, and the collar 13 can be held in a selected position of vertical adjustment by tightening the wingnuts 22 on the screws 21. By being provided with the adjustable collar 13, the invention is adaptable to a variety of supporting surfaces and at the same time presents the appearance of having been designed especially to fit the particular contour of the surface to which it is attached. The invention provides a convenient, sanitary, ventilated receptacle which is very neat in appearance.

The adaptability to a variety of attaching surfaces and the neat appearance above referred to is of particular interest to tavern owners having the modern type of bar fixture which is in vogue at the present time. Certain curved bar fixtures now in use give the patron a full view of much equipment which was formerly hidden by the old straight line type of bar. This open type of bar design not only requires the use of equipment which is neat in appearance, but it also requires equipment which promotes the utmost sanitation. By providing a ventilated receptacle for the bar cloth, contamination of glasses, water bottles and the like is prevented, and the cloth is stored in a convenient place away from the patron and substantially concealed from his view.

Various changes and modifications may be made without departing from the spirit of the invention, and all of such changes are contemplated, as will come within the scope of the claims.

What we claim is:

1. A receptacle comprising an elongated perforated body section having a bottom wall, having side walls, and having a wall at one end, the opposite end being open, said body section being formed with means for attachment thereof to the lower side of a support, and a plate vertically movably supported on said end wall for varying the height thereof to conform to the contour of the lower side of said support.

2. A receptacle comprising an elongated perforated body section having a bottom wall, having side walls and having a wall at one end, the opposite end being open, said body section being formed with means for attachment thereof to the lower side of a support, and a U-shaped extension member slidably overlapping said end

wall and adjacent portions of said side walls to vary the effective height of said wall portions to conform to the contour of the lower side of said support.

3. A receptacle comprising an elongated perforated body section having a bottom wall, having side walls, and having a wall at one end, the opposite end being open, said body section being formed with means for attachment thereof to the lower side of a support, a U-shaped extension member slidably overlapping said end wall and adjacent portions of said side walls to vary the effective height of said wall portions to conform to the contour of the lower side of said support, and at least one screw projecting through said body section and said extension member for locking said extension member in a selected position of adjustment.

4. A receptacle comprising an elongated body section having a bottom wall, having side walls, and having a wall at one end, the opposite end being open, said body section being formed with means for attachment thereof to the lower side of a support, a U-shaped extension member slidably overlapping said end wall and adjacent portions of said side walls to vary the effective height of said wall portions to conform to the contour of the lower side of said support, and at least one screw projecting through said body section and said extension member for locking said extension member in a selected position of adjustment.

20 5. A receptacle comprising an elongated body section having a bottom wall, having side walls, and having a wall at one end, the opposite end being open, said body section being formed with means for attachment thereof to the lower side of a support, a U-shaped extension member slidably overlapping said end wall and adjacent portions of said side walls to vary the effective height of said wall portions to conform to the contour of the lower side of said support, said extension member being formed with elongated vertical slots, and locking screws projecting from said body section and extending through said slots for locking said extension member in a selected position of vertical adjustment.

30 6. A receptacle comprising an elongated perforated body section having a bottom wall, having side walls, and having a wall at one end, the opposite end being open, said body section being formed with means for attachment thereof to the lower side of a support, and a U-shaped extension member slidably overlapping said end wall and adjacent portions of said side walls to vary the effective height of said wall portions to conform to the contour of the lower side of said support, said extension member also being formed with means for connection to the lower side of said support.

40 7. In a combination, a shelf member formed with a downwardly offset trough along a margin thereof, and a perforated receptacle having an elongated body section attached to the underside of said trough, said body section having a bottom wall, having side walls, and having an end wall, the other end of said body section adjacent the edge of the shelf being open, said receptacle having a U-shaped extension member slidably overlapping said end wall and adjacent portions of said side walls, said extension member being positioned in contact with the underside of said shelf member beyond said trough.
